TIE WIRE FASTENER AND KEY

Filed Oct. 23, 1929

UNITED STATES PATENT OFFICE

ELMER C. PITCHER, OF HAYWARD, CALIFORNIA

TIE WIRE FASTENER AND KEY

Application filed October 23, 1929. Serial No. 401,890.

My invention relates to improvements in tie wire fasteners and keys, and it consists in the combinations, constructions and arrangements hereinafter described and claimed.

5 An object of my invention is to provide a tie wire fastener and key that is designed especially for securing wall board to a metal stud for providing a hollow wall construction. The tie wire fastener has openings for 10 the wire that are inclined with respect to the axis of the wire. This causes the fastener to grip the wire.

The tie wire fastener, in conjunction with the tie wire, provides a key for holding plaster to the wall board. The tie wire is bent 15 so as to have its end engage with the fastener, and the bent portion provides a space between the wire and the fastener which receives plaster. In this way the device acts as a key for 20 the plaster.

A further object of my invention is to provide a device of the type described which is extremely simple in construction and which cuts down the amount of time required to secure wall board to the studs. The 25 means used in bending the tie wire into place also pulls the wire taut, and this insures a firm connection between the stud and the wall boards. Where fibrous wall boards or 30 plaster boards are used, the fastener acts as a washer for preventing the wire from becoming embedded in the wall board, which would result in the loosening of the construction.

35 Other objects and advantages will appear as the specification proceeds, and the novel features will be particularly pointed out in the claims hereto attached.

My invention is illustrated in the accompanying drawing, in which:

Figure 1 is a front elevation of the device,
Figure 2 is a section along the line 2-2 of

Figure 1,

Figure 3 is a perspective view of the fastener,

Figures 4 and 5 show how the tie wire is secured in place,

Figure 6 is a sectional view of a modified form of the device,

50 Figure 7 is a plan view of Figure 6,

Figure 8 is a longitudinal section through the form of fastener shown in Figure 8.

In carrying out my invention, I provide a plurality of metal studs 1 that have openings 2 therein.

Wall boards 3 formed of compressed fibrous material or wall board are disposed on either side of the studs and are locked to the studs in a manner now to be described.

I force a tie wire 4 of the shape shown in Figure 5 through one of the plaster boards 3, then through the aligned openings 2-2, and then through the opposite plaster board 3. When the wire is first forced into place, it has a bent end 5 and a straight end portion 6. A fastener 7 of the shape shown in Figure 3 is first mounted upon the wire 4 prior to its entrance into the plaster boards. The bent end 5 is inserted in a recess 8 in the upturned portion 9 of the fastener 7. The tie 70 wire 4 passes through an opening 10 in the fastener 7, and it will be noted from Figure 3 that this opening is inclined away from the recess 8.

From the description thus far, the wire and fastener 7 will take the appearance shown in Figure 4. A similar fastener 7 is now applied to the other end of the wire. The opening 10 in this fastener is such as to tend to prevent movement of the tie wire with respect to the fastener when the fastener extends at right angles thereto. The operator in securing the other end of the tie wire in place, grips the projecting end portion 6 of the tie wire with pliers indicated generally at 11 and rocks the 85 pliers into the dotted line position shown in Figure 4. The pliers have a blunt jaw end 12, and therefore the rocking of the pliers in a clockwise direction will pull the tie wire 4 taut and will press the wall board 3 firmly 90 against the metal stud 1 and the fastener 7 against the wall board. This pulling of a slight portion of the wire through the opening 10 at the same time the portion 6 of the wire is bent into the position A shown in Figures 4 and 5 will securely fasten all of the parts together and will prevent the slipping of the fasteners on the wires. After the portion 6 has been bent into the position A, it may 95 be further bent into the position B shown in 100

Figure 5 and also shown in Figure 2. In the position B the portion 6 is received in the recess 8 of the fastener 7. The parts are now securely locked together.

5 The recesses 8 in the fasteners 7 prevent rotation of the tie wire 4 with respect to the fastener 7, and in this way the edges of the inclined openings 10 frictionally engage with the tie wire 4 and prevent slippage between the tie wire and the fasteners. The fasteners also prevent the relatively thin tie wire from having its ends 5 and 6 become embedded in the fiber or plaster board 3 and thus loosen the connection between the boards and the 15 metal stud 1.

10 The co-action between the fastener 7 and the ends of the tie wire provide a key for the plaster which will form a lock between the plaster 12 and the wall board 3. It will be 20 noted from Figures 2 and 4 that a space 13 is provided between the bent ends of the tie wire and the fastener members 7. This space receives the plaster while the plaster is still in a plastic state. When the plaster hardens, the ends 5 and 6 will be embedded in the 25 plaster, and in this way the device acts as a key for locking the plaster to the boards. In Figure 1, I show two of the devices, the lower one being embedded in the plaster 12 while the upper one is shown bearing against the 30 plaster board 3, the plaster being removed from the upper one for clarity. The device is extremely simple in construction, and performs a number of functions.

35 In Figures 6 and 7, I show a slightly modified form of the device. The fastener 25 in this form of the device consists of a flat piece of metal without any turned-up portion. The piece of metal 25 has a recess 26 therein that corresponds with the recess 8.

40 The tie wire 27 has a curved portion 28 disposed at one end, and the plane of this curved portion extends at right angles to the axis of the wire. The curved portion acts as a head 45 and abuts against the plaster board 3.

45 The other end of the tie wire is passed through an inclined opening 29 in the plate 25 similar to the opening 10, and the end of the wire is bent over by means of the pliers 11 in the same manner as the end 6 of the wire 4 is 50 bent into the position A. The bent end 30 is then hammered down so as to be received within the recess 26. The end 30 and the fastener 25 form a key for the plaster. The other 55 parts of the device are the same as that already set forth, and similar reference numerals will therefore be applied to these parts.

60 Although I have shown and described two embodiments of my invention, it is to be understood that the same is susceptible of various changes, and I reserve the right to employ such changes as may come within the 65 scope of the invention as claimed.

I claim:

1. A hollow wall construction comprising studs, wall boards disposed on opposite sides of said studs, tie wires extending through said wall boards, and fasteners disposed on the ends of said wires and having inclined openings for receiving the wires and whose walls grip the wires and prevent them from becoming loosened. 70

2. A hollow wall construction comprising 75 studs, wall boards disposed on opposite sides of said studs, tie wires extending through said wall boards, fasteners disposed on the ends of said wires and having inclined openings for receiving the wires and whose walls grip the wires and prevent them from becoming loosened, and means carried by the fasteners for preventing rotation of the wires in the openings. 80

3. A hollow wall construction comprising 85 channel irons having aligned openings therein, wall boards disposed on the opposite sides of said channel irons, tie wires passed through the boards and aligned openings, fasteners disposed on the ends of the tie wires and having inclined openings for receiving the wires, the ends of the wires being bent oppositely to the inclination of the openings, and means carried by said fasteners for holding the wires against rotation in said 90 openings. 95

4. A hollow wall construction comprising channel irons having aligned openings therein, wall boards disposed on the opposite sides of said channel irons, tie wires passed through the boards and aligned openings, fasteners disposed on the ends of the tie wires and having inclined openings for receiving the wires, the ends of the wires being bent oppositely to the inclination of the openings, and means carried by said fasteners for holding the wires against rotation in said 100 openings, said means spacing the bent ends of the wires from the fasteners for forming a 105 plaster key. 110

5. An article of manufacture comprising a single angle-shaped member having a flat side of substantial thickness with an opening whose axis is inclined slightly with respect to a line extending at right angles to the 115 plane of the side. 115

6. An article of manufacture comprising a single angle-shaped member of substantial thickness and having an inclined opening in one side and a recess in the other side. 120

7. An article of manufacture comprising a tie wire fashioned with a head at one end, and a flat member of substantial thickness and having an oblique opening for slidably receiving the other end of the wire, the wall 125 of the opening gripping the wire when the member extends at right angles to the axis of the wire, whereby relative movement between the wire and member is prevented.

8. An article of manufacture comprising 130

an angle-shaped wire anchor having a recess in one side and an opening in the other, the axis of the opening being inclined away from the side having the recess, the anchor being thick enough at the opening to prevent the bending of the edge of the opening.

9. An article of manufacture comprising an angle-shaped wire anchor having a recess in one side and an opening in the other, the axis of the opening being inclined away from the side having the recess, and a tie wire for holding forms together and being received in the opening, and having its end bent so as to be received in the recess, the anchor being thick enough at the opening to prevent the bending of the edge of the opening.

10. An article of manufacture comprising a base having an opening extending at an inclination relative to the surface thereof, and adapted to receive a wire with the end of the latter bent over the sharp edge defined by the opening, the base being thick enough at the opening to prevent bending of the edge of the opening, and means for holding the free end of the wire against movement.

11. An article of manufacture comprising a base having an opening extending at an inclination relative to the surface thereof, and adapted to receive a wire with the end of the latter bent over the sharp edge defined by the opening, the base being thick enough at the opening to prevent bending of the edge of the opening, the base being formed with an opening for receiving the free end of the wire for holding the latter against movement.

12. An article of manufacture comprising a base having a wire receiving opening therein extending at an inclination relative to the base surface, and defining a pronounced wire engaging lip for stopping slippage of the wire, the base being thick enough at the opening to prevent bending of the edge of the opening.

13. An article of manufacture comprising a tie wire for holding wall forms together, and fasteners of substantial thickness, having openings for receiving a wire, the openings having their axes slightly inclined for causing the walls of the openings to frictionally engage with the wire.

14. An article of manufacture comprising a tie wire for holding wall forms together, and fasteners of substantial thickness, having openings for receiving a wire, the openings having their axes slightly inclined for causing the walls of the openings to frictionally engage with the wire, said fasteners also having recesses for receiving the ends of the wire, the walls of said recesses preventing the rotation of the wire in the openings.

ELMER C. PITCHER.
